DESIGN FOR A SEAL CUTTER FOR BOTTLES, OR SIMILAR ARTICLE

William C. Lanyon, Waukegan, Ill.

Application April 23, 1945, Serial No. 119,138

Term of patent 3½ years

(Cl. D22—3)

To all whom it may concern:

Be it known that I, William C. Lanyon, a citizen of the United States, residing at Waukegan, in the county of Lake and State of Illinois, have invented a new, original, and ornamental Design for a Seal Cutter for Bottles, or Similar Article, of which the following is a specification, reference being had to the accompanying drawing, forming part thereof.

Figure 1 is a plan view of a seal cutter for bot-

ties, or similar article, showing my new design, Figure 2 is a bottom plan view, Figure 3 is an edge elevational view, and Figure 4 is an elevational view of the opposite edge thereof.

I claim:

The ornamental design for a seal cutter for bottles, or similar article, as shown.

WILLIAM C. LANYON.
